FRANK L. DODGSON, OF ROCHESTER, NEW YORK, ASSIGNOR TO GENERAL RAILWAY SIGNAL COMPANY, OF ROCHESTER, NEW YORK

MEANS FOR CHECKING TRACKWAY DEVICES

Application filed April 2, 1925. Serial No. 20,144.

This invention relates to trackway apparatus for train control systems of the intermittent type, and more particularly to means for preventing the wayside signal adjacent to the trackway device from indicating clear or proceed whenever such trackway device is in a danger traffic condition even though it is in such condition by reason of failure of an essential part or circuit of such trackway device.

Influence communicating means for transmitting control influences from the trackway to the moving train in train control systems of the intermittent type and especially if such influence communicating means is used to transmit influences corresponding to adverse traffic conditions ahead, are constructed to function on the side of safety, that is, are constructed on the closed circuit principle, so that, the failure of a circuit or circuits thereof causes an influence to be communicated. In systems of this kind the failure of such circuit of the influence communicating means causes a control influence to be transmitted even though the wayside signal indicates clear and traffic conditions ahead are favorable. It is especially bad to transmit a stopping control influence to a moving train when the signal adjacent thereto is in a clear condition in systems of the automatic stop type (systems in which the transmission of an influence effects a brake application), because a sudden and unexpected brake application, which in itself is dangerous, takes place upon passage of the train by a defective trackway device. This is also true of permissive systems or systems of the speed control type employing acknowledging features, because in these latter systems a brake application takes place by reason of the failure of the engineer to manifest his vigilance when passing such a defective trackway device even though the engineer was vigilant in looking out for wayside signals in a restrictive condition and passed no such signal. An unex-

pected brake application in systems of the latter type does not only necessarily restrict the speed of the train but may result in wrecking a train.

In accordance with the present invention, which has been shown applied only to ramp systems and systems employing trackway devices of the inert inductor type in which type a circuit of low resistance is closed under clear traffic conditions ahead, it is proposed to cause the signal adjacent to which such trackway device is placed to assume the danger condition, or at least, again fail to assume the clear condition after once having assumed the danger condition, if the trackway device is in its danger and influence communicating condition by reason of the fact that it is constructed on the closed circuit principle and is out of order. Another object of the present invention resides in the provision of means which causes a wayside signal to assume its danger position if the trackway influence communicating device adjacent thereto is accidentally or maliciously taken away.

Other objects, purposes and specific features of the invention will in part be pointed out and in part be obvious from the description hereinafter given.

In describing the invention in detail reference will be made to the accompanying drawings in which:

Fig. 1 illustrates a control point of the trackway apparatus of a train control system of the intermittent type in which the pick up circuit for a stick home relay is completed through the low resistance coil of the trackway device so as to check the integrity thereof;

Fig. 2 illustrates apparatus identical to that shown in Fig. 1, except that there is also a check relay and a source of direct current in the circuit of the low resistance coil;

Fig. 3 shows an arrangement similar to that shown in Fig. 2, but wherein the check relay is located in the common wire of two

circuits in multiple each including a part of the low resistance coil, and in which a resistance is at times connected in series with this check relay and source of current; and

5 Fig. 4 shows an arrangement of the invention similar to that shown in Fig. 2 but applied to a ramp system.

Structure (Fig. 1)

10 Referring more particularly to Fig. 1 of the drawings, there have been shown track rails 1 divided by insulating joints 2 into blocks in the usual manner, of which the block I and the adjacent ends of the blocks 15 K and J only have been illustrated. At the entrance end to each block, as illustrated, for the block J is shown the usual track relay T which by the aid of the usual track battery (shown for the blocks I and J) responds to 20 traffic conditions of the block, that is, assumes the deenergized and energized position if the block is occupied and unoccupied respectively. The home relay H reflects traffic conditions of a portion of the track- 25 way in advance thereof, and is controlled in the usual way. In the particular arrangement shown the circuit of the home relay H includes in series therewith the front contacts of the track relays T and T^a of the two 30 sections of the block J. Further, a distance relay D is provided which is controlled by the home relay H of the block in question and the home relay of the block next in advance. The relay D in combination with the home 35 relay H control a three-position semaphore signal Z of the usual construction, and for convenience this semaphore signal Z has been shown conventionally without illustrating its control mechanism and by merely showing its clear and caution control circuits cl and ca respectively leading into the signal.

40 Adjacent the signal Z and preferably a short distance in the rear thereof, the normal direction of traffic being as indicated by the arrow, is located an influence communicating device E, which in the specific arrangement shown is one of the inert inductor type and comprises a core 4 of laminated magnetic material terminating in upwardly facing pole 45 pieces 5 and having a coil 6 on the back yoke thereof, which coil is closed in a circuit of low resistance when this device is in its ineffective or non-influence communicating condition.

50 55 Under normal clear traffic conditions of the particular apparatus shown, the home relay H is energized through a circuit beginning at the battery 8 located at the next signal Z¹ in advance, wire 9^a, contact 10^a of relay T^a, wire 9, front contact 10 of the track relay T, winding of the home relay H, wire 11, coil 6 of the track element E, wires 14 and 15 to a common return wire C connected to the other terminal of said battery, so that 55 this relay H can be picked up if the complete

block J is unoccupied. Similarly, distant relay D is picked up by a pick-up circuit beginning at the battery 8 of the block in advance, through contact 20' of the relay H' of the signal location in advance, the contact 21' operated by the signal blade of the signal at the signal location in advance and closed under both clear and caution conditions of such signal, wire 16 front contact 17 of the home relay H of the signal location in 75 question, winding of the distant relay D of the signal location in question, wire 18, coil 6 of the track element E, wires 14 and 15 back to the common return wire C. It should be noted that the circuit for the relays H and D just traced are pick-up circuits, and that the stick circuits for these relays include the contact 12 of the relay D which relay D is controlled by relay H. In other words, the integrity of the coil 6 is necessary to pick up 80 relays H and D, but such integrity is not necessary to hold the relays H and D energized if they have once assumed their energized condition.

Operation (Fig. 1)

90 In order to understand how the embodiment of the invention illustrated in Fig. 1 causes the signal Z to assume the danger position if an open circuit develops in the low 95 resistance coil of the track element E, let us assume that the apparatus shown in Fig. 1 is in its normal clear traffic condition as illustrated and that there is a train moving from left to right from the block I into the block J. As soon as the train gets into the block J the track relay T is de-energized thereby dropping the home relay H and in turn the distant relay D. Dropping of the home relay H opens both the caution circuit ca and the clear circuit cl, this clear circuit cl also being opened by dropping of contact 19 of the distant relay D, so that the signal Z assumes its danger indicating position. These circuits include the battery 8^a and the front contact 10 of the home relay H and are readily traced in the drawing. Dropping of the distant relay D opens the circuit for the low resistance coil 6 by dropping its contact 12, so that the trackway device E is now in its active 110 stopping condition. Let us assume that due to the vibration of this train, or the like, as it passes this control point, an open circuit develops in the coil 6 of the track element E, so that, this device is permanently in its active condition regardless of the position of the contact 12. Let us further assume that the train proceeds and finally gets out of the block J and enters into the next block in advance thereof, so that the track relay T again picks up. Even though the contact 10 of the track relay T is closed, the pick up circuit for picking up the home relay H is not closed, because this circuit includes the coil 6 of the track element E which has been 120 125 130 135 140 145 150

assumed to be open by reason of a break in this coil or in the lead wires leading thereto, and consequently the home relay H cannot pick up. Similarly, the distant relay D cannot pick up even though the contact 21¹ of the signal Z¹ ahead is closed, because its pick up circuit includes the coil 6 which is assumed to be open-circuited and includes the front contact 17 of the home relay H which relay is de-energized, so that, both of these relays remain de-energized in spite of the fact that traffic conditions ahead are clear, and the signal Z remains in the danger position by reason of the fact that the coil 6 of the track element E is open-circuited, as assumed.

The arrangement shown in Fig. 1 although it takes care of the most common breaks in the low resistance circuit including the coil 6 does not check this entire circuit, because the front contact 12 of the distant relay D which forms a part of this low resistance circuit has not been checked, the pick up circuit for the home relay H including only wire 11, coil 6 and the leads extending therefrom, and wires 14 and 15, so that if a bad contact should develop at contact 12 the device E might still be in its influence communicating condition under clear traffic conditions ahead and while the signal Z is in its clear indicating position.

Also, if an open circuit should develop in the coil 6 while there are no trains around and while the signal Z is in its clear traffic condition, the development of this open circuit would cause the track element E to be in its effective stopping condition, and out of correspondence with the signal Z which remains in its clear traffic indicating position, and the occurrence of an open circuit at this time of course does not change the signal Z, because the stick circuit for the relays H and D are now completed through the contact 12 of the distant relay D. In other words, the check provided in the arrangement shown in Fig. 1 is only effective to prevent the signal from changing from an adverse condition to a clear traffic condition upon opening of the circuit including the low resistance coil 6, and the arrangement shown does not place the signal Z in the danger position if it has once assumed its clear traffic position.

In order to further check the integrity of the circuit including the coil 6, it has been proposed to place a check relay in this circuit together with a source of energy to detect its integrity, and such an arrangement is shown in the embodiment illustrated in Fig. 2. It should be noted that the line wires of the block I corresponding to those of the block J have been designated by like reference characters having a distinctive exponent zero.

Structure (Fig. 2)

The embodiment of the invention illustrated in Fig. 2 of the drawings is exactly the same as that shown in Fig. 1 except that

a check relay CK and a battery 25 connected in series in the circuit including the low resistance coil 6 of the track element E are provided, and that a front contact 26 of this check relay CK is connected in the clear circuit cl of the signal Z, and for this reason the various like parts shown in Fig. 2 of the drawings have been designated by the same reference characters as those in Fig. 1.

Operation (Fig. 2)

Obviously, the same principle for checking the integrity of the low resistance coil 6 of the track element E as explained in connection with Fig. 1 of the drawings is present in the arrangement shown in Fig. 2; that is, if the next signal in advance once assumes an adverse traffic indicating position and the front contact 12 of relay D is open for this reason and the coil 6 of device E is open, for some reason the relay H cannot again be picked up because its pick-up circuit is broken at coil 6 and therefore the signal Z associated therewith cannot assume its clear indicating position. In addition to this check, there is provided a check relay CK so that if an open circuit develops in the coil 6 while the signal Z is in its clear position the check relay CK is deenergized because its energizing circuit is open at the break in coil 6 and in turn drops its contact 26 and opens the clear circuit cl so that the signal Z assumes its caution position. This check relay of course also takes care of a high resistance contact at the contact 12, which as heretofore mentioned is a part of the circuit which can not be checked by the arrangement shown in Fig. 1. In practice the check relay CK is designed so that it assumes its de-energized position due to a reduction in the current flow therein if the resistance of the contact 12 is high enough to cause the track element E to transmit a control influence to a passing train. In other words, if at any time the resistance of the bucking circuits, including coil 6, relay CK and the contact 12 increases to a value which renders the device E active the check relay CK will drop and the signal will go to caution. Since the current for energizing the check relay CK must

flow through the low resistance coil 6 of the track element E a weak magnetic field emanates from the pole pieces of this track element. This field although it is very weak is preferably so poled that it opposes the magnetism set up by the primary coil of the car apparatus to be used therewith, such, for instance, as shown in the application of F. L. Dodgson, Ser. No. 726,781, filed July 18, 1924. In other words, the weak field produced by the track element E slightly opposes the transmission of a control influence and thereby improves the operation of the system, or rather, is less apt to cause a transmission of a control influence under clear traffic condi-

tions, that is, when this coil 6 is closed in a circuit including the check relay C_k and the battery 25.

In the arrangements shown in Figs. 1 and 2 the trackway influence communicating device E and the signal Z are both operated separately by the relays D and H. For reasons already given the system shown in Fig. 2 is such that failure of the track element E to be in a condition corresponding to traffic conditions ahead when such traffic conditions are favorable causes the signal Z to assume a condition corresponding to that of the track element E in spite of favorable traffic conditions ahead. In addition to this possible discrepancy between the operating conditions of the track element E and the signal Z, the signal Z may be in the danger indicating position by reason of its being out of order and being constructed to function on the side of safety; and if it is desired to bring the track element E into harmony with the signal under such conditions an additional contact, operated by the signal Z and closed when the signal is at clear is connected in series with the contact 12 of the relay D.

Structure (Fig. 3)

The arrangement shown in Fig. 3 of the drawings is very similar to that shown in Fig. 1 and differs therefrom only in slight details presently pointed out, and therefore like parts have been assigned like reference characters. In the arrangement shown in Fig. 3 the front contact 19 of the distant relay D has been omitted. Further, the coil 6 of the track element E has a tap brought out from the mid-point of its winding which is connected to a wire including the check relay, the battery 25, and a resistance 29, which resistance is at times short-circuited by the contact blade 27 of the signal Z, this circuit dividing into two branches each including one half of the low resistance coil 6. This arrangement is provided so that the current for energizing the check relay C_k divides itself into two components and these components flow through the winding of the coil 6 in opposite directions, so that one component neutralizes the other and so that there is no magnetic field emitted by the track element E. Since in the arrangement shown in Fig. 3 the coil 6 is divided into two parts one of which may be shunted by the contact 12 of the relay D, an additional contact 28 has been provided on this relay D which contact shunts in the other portion of this coil 6.

Operation (Fig. 3)

The operation of the system shown in Figs. 2 and 3 is identical, so that the operation of the system shown in Fig. 3 need not be considered in detail. It should, however, be noted that there is no magnetic field emitted by the track element E by reason of

the fact that the current flowing in check relay C_k flows through the coil 6 in two components which neutralize each other, and that if an open circuit occurs in one part of the coil 6 or its associated lead wire that the current flow through the check relay C_k is not entirely cut off, but is merely reduced in value, because the current flowing in one of the two circuits in multiple has discontinued to flow. In order to assure that this check relay C_k will assume its de-energized position in response to the small change in current flow effected if one part of the coil 6 becomes open circuited, the resistance 29 has been provided in this circuit which resistance 80 is shunted by contact 27 when the signal Z is at caution or danger. The various constants of the circuit including the check relay C_k , battery 25 and resistance 29 are in practice so chosen that the check relay C_k cannot pick up when one of the portions of coil 6 is open circuited due to circuit failures, or the like, even though the resistance 29 is shunted by contact 27, and so that the check relay is sure to drop if one portion of the coil 6 is open circuited and contact 27 is open. In order to get a clearer understanding of this portion of the arrangement shown in Fig. 3 let us assume that the signal is at clear and one of the portions of coil 6 is open-circuited. This will cause the check relay C_k to drop, which in turn by dropping contact 26 causes the signal Z to assume the caution position. With the signal Z at caution the resistance 29 is shunted by contact 27 but in spite of the increase in the current due to this reduction in the resistance of this circuit, insufficient current to pick up the check relay C_k will flow. In other words, the resistance 29 and contact 27 have been provided so that if the current flowing in the check relay has been reduced to a value so that this relay can not pick up, this relay will assume its de-energized position, although it already was in its picked up position when the current was so reduced, this additional resistance being inserted in series therewith when the check relay should assume its de-energized position and if it is still in its energized position this insertion of resistance causes it to assume 110 its de-energized position, whereby even though this additional resistance is again shunted out of the circuit the relay is unable to again pick up.

Structure (Fig. 4)

In Fig. 4 has been illustrated a ramp system to which the present invention is applied, showing a ramp R which under clear traffic conditions has a potential with respect to the ground applied thereto, and more particularly with respect to the track rails, as is common in train control systems of the ramp type. In the arrangement shown, this application of potential is effected by 130

the closure of a partial circuit including the front contact 30 of the distant relay D and a suitable source of energy, this source of electrical energy which may be either alternating or direct in character being for convenience illustrated as comprising a battery 31. In order to assure that the signal indication of the wayside signal Z corresponds to that of the condition of the ramp when this ramp, by reason of an open circuit or the like, is not in its clear traffic condition when it should be, a check relay Ck is connected between a certain point on this ramp and the track rails, so that this check relay Ck assumes the energized condition whenever the ramp R is energized. This check relay Ck, of course, has an internal resistance of a value that does not interfere with the proper operation of the car relay (not shown), and further has characteristics such that it is not effectively shunted by such car relay or effected in any other way by the passage of a train equipped with the usual contact shoe and car relay. This check relay Ck as well as the various circuits controlled thereby are the same as corresponding devices shown in Fig. 2 of the drawings and already described, except that the energizing circuits for the relays H and D go directly to the common return wire C instead of including a front contact 12 of the relay D.

Operation (Fig. 4)

The signal Z in Fig. 4 of the drawings is governed by the relays H, D and Ck in exactly the same way as is the signal in Fig. 2, that is, the signal cannot assume or remain in the clear position if the check relay Ck is in the de-energized position, this because the clear or 90° wire cl includes both the contact 30 of the distant relay D and the front contact 26 of the check relay Ck. The functioning of the check relay Ck is of course understood, this relay being one of the potential type the same as the usual car relay employed in ramp systems, and this check relay is momentarily connected in multiple with such car relay upon the passage of a train. When there is no train passing by and traffic conditions ahead are clear, this check relay is connected directly across the battery 31 through the front contact 30 of the distant relay D, so that the signal only assumes the clear or proceed condition when the ramp R is energized.

It should be noted that, by reason of the fact that the pick-up circuits for the home relays H of Figs. 1, 2 and 3 include the coil 6 of the trackway element E, the signal adjacent to an element having its coil open circuited accidentally must assume the danger position; whereas in Fig. 4 the signal is only prevented from assuming the clear position when the energizing circuit for the ramp R is accidentally broken, that is, may either as-

sume the caution or danger position depending on traffic conditions ahead. Either of these expedients are considered safe, but in the event the signal is caused to assume the danger position as it is in Figs. 1, 2 and 3, the next signal in the rear should be directly governed by the signal in question and not only by the several relays which indicate actual traffic conditions ahead, in order that an approaching train will be properly informed by a caution signal before it reaches a signal at stop by reason of failure of a trackway device.

Having thus shown and described several specific embodiments of the invention, it is desired to be understood that the specific arrangements shown have been selected for the purpose of illustrating its scope or the exact construction preferably employed in practice, and that various changes and modifications may be made to adapt the invention to the particular type of influence communicating means employed in connection with the train control system to which the present invention is to be applied, for instance, if the present invention is to be applied to a system in which the trackway device includes a permanent magnet and a deflecting or bucking coil, which coil is energized under clear traffic conditions, the direct current for energizing this bucking coil may be employed to control the check relay, without departing from the scope of the invention or the idea of means underlying the same.

What it is desired to be secured by Letters Patent is:—

1. Trackway apparatus for train control systems of the intermittent inductive type, comprising the combination of a wayside signal controlled in accordance with traffic conditions ahead of such signal for the particular direction of traffic controlled by said signal, and inductive trackway device including a coil closed in a deenergized circuit of low resistance when said trackway device is in its clear inactive condition, a relay having its winding connected in series with said coil and adapted to change from its de-energized to its energized condition only if said coil is intact, said relay placing said wayside signal in an adverse traffic indicating condition when said relay assumes its de-energized condition, whereby said signal indicates danger if said coil is accidentally open-circuited.

2. Trackway apparatus for train control systems of the intermittent inductive type, comprising the combination of a wayside signal controlled in accordance with traffic conditions ahead of such signal for the particular direction of traffic controlled by said signal, an inductive trackway device including a coil which is connected in a closed deenergized circuit of low resistance under favorable traffic condition ahead, a relay hav-

ing its winding at times connected in series 5 with said coil, and means for causing said way side signal to indicate adverse traffic conditions regardless of traffic conditions ahead when said relay is de-energized, whereby said signal will be in correspondence with said device when said coil is accidentally open-circuited.

3. Trackway apparatus for automatic 10 train control and signalling systems comprising, a wayside signal, traffic responsive means including a relay for controlling said signal, an inductive traffic controlling device for transmitting control influences to a moving 15 vehicle under adverse traffic conditions ahead including a coil which if closed circuited places said device in its inactive condition, said coil being contained in the energizing circuit of said relay and said relay having a contact in multiple with said coil 20 closed when said relay is energized, whereby said relay can only assume its energized condition in response to a favorable change in traffic conditions ahead if the circuit of said 25 coil is intact.

4. Trackway apparatus for automatic 30 train control and signalling systems comprising, a wayside signal, traffic responsive means including a relay for controlling said signal, and inductive traffic controlling device for transmitting control influences to a moving 35 vehicle under adverse traffic conditions ahead including a coil which if closed circuited places said device in its inactive condition the energizing circuit of said relay including a front contact thereof so that its energizing circuit is a stick circuit, said coil being bridged across said front contact so that this coil provides a pick up circuit for 40 said relay, whereby said relay can be picked up in response to a favorable change in traffic conditions only when the winding of said coil is intact.

5. Trackway apparatus for automatic 45 train control and signalling systems comprising, an inductive influence communicating track element which is inactive when a coil associated therewith is contained in a closed circuit, said track element being governed in 50 accordance with traffic conditions ahead, a wayside signal located adjacent said track element and controlled in accordance with traffic conditions ahead, and means for causing said signal to assume a condition indicating 55 adverse traffic conditions ahead regardless of traffic conditions ahead when said coil is open-circuited, whereby the indication of said signal will correspond to the condition of said track element by reason of failure of 60 the coil of said track element.

6. Trackway apparatus for automatic 65 train control and signalling systems comprising, an inductive influence communicating track element which is inactive when a coil associated therewith is contained in a closed

circuit, said track element being governed in accordance with traffic conditions ahead, a wayside signal located adjacent said track element controlled in accordance with traffic conditions ahead, and means for preventing 70 said signal from again assuming a favorable traffic indicating conditions after once having assumed an adverse traffic indicating condition even though traffic conditions ahead are favorable if said coil accidentally becomes 75 open-circuited.

7. Trackway apparatus for automatic train 80 control and signaling systems, the combination of a wayside signal, a trackway device for inductively transmitting control influences to 85 a moving train under adverse traffic conditions ahead constructed so as to have an inherent tendency to assume such active condition and having an electrical circuit associated therewith effective under clear traffic 90 conditions to remove such tendency, and means for causing said signal to assume a favorable traffic indicating condition when said circuit is closed and for causing it to assume unfavorable traffic indicating condition 95 when said circuit is open.

8. Trackway apparatus for automatic train 100 control and wayside signaling systems comprising, a wayside signal, trackway means for transmitting control influences inductively to 105 an approaching train, said means including a circuit and manifesting favorable traffic conditions if said circuit is closed and manifesting unfavorable traffic conditions if said circuit is open, and means for causing said wayside signal to indicate favorable traffic conditions when said circuit is closed and to indicate unfavorable traffic conditions when said circuit is open.

9. Trackway apparatus for automatic train 110 control and signalling systems comprising, an inductive trackway device having a coil thereon and inactive to transmit control influences when said coil is closed in a de-energized 115 circuit of low resistance, a wayside signal, means for detecting the integrity of the circuit containing said coil including a relay and a source of energy, means for causing said signal to assume a proceed position when said relay is energized, and means including another circuit for neutralizing the effect of the current due to said source of energy upon said device.

10. Trackway apparatus for automatic 120 train control and wayside signal systems comprising, a wayside signal, a trackway device for transmitting control influences to suitable vehicle carried means and having a circuit portion which must be intact in order to permit said trackway device to manifest favorable 125 traffic conditions, a stick relay for governing said trackway device and said wayside signal and having a front contact closed when said relay is energized, a stick circuit including the winding and the front contact of said 130

relay, a pick-up circuit for said relay including the winding of said relay and said circuit portion, said wayside signal and said trackway device indicating favorable traffic conditions when said relay is energized and indicating unfavorable traffic conditions when said relay is de-energized, whereby the failure of integrity of said circuit portion causes said signal to indicate adverse traffic conditions.

11. Trackway apparatus for automatic train control and wayside signalling systems comprising, a wayside signal, trackway means for transmitting control influences inductively to an approaching train, said means including a coil and manifesting favorable traffic conditions if said coil is included in a closed circuit of low resistance and manifesting unfavorable traffic conditions if the circuit of said coil is open, and means for permitting said wayside signal to indicate favorable traffic conditions only when the circuit for said coil is closed and for causing said signal to indicate unfavorable traffic conditions when said circuit is open.

12. Trackway apparatus for automatic train control and signalling systems, the combination of a wayside signal, a trackway device for inductively transmitting control influences to a moving train under adverse traffic conditions ahead constructed so as to have an inherent tendency to assume such active condition and having a coil associated therewith which if included in a circuit of low resistance will remove such tendency and which under clear traffic conditions is included in a circuit of low resistance, and means for permitting said signal to assume a favorable traffic indicating condition when said coil is electrically intact and for causing said signal to assume an unfavorable traffic indicating condition when the integrity of the circuit of said coil is broken.

13. Trackway apparatus for automatic train control and signalling systems comprising, an inductive trackway device having a coil thereon and inactive to transmit control influences when said coil is closed in a de-energized circuit of low resistance, a wayside signal, means for detecting the integrity of the circuit containing said coil including a relay and a source of energy, means for causing said signal to assume a proceed condition when said relay is energized, means including another circuit for neutralizing the effect of the current due to said source of energy upon said device, and means for inserting additional resistance in series with said relay under clear traffic conditions so that if either said first mentioned circuit or said another circuit is broken while clear traffic conditions exist insufficient current to maintain said relay energized will flow.

14. Railway traffic controlling apparatus comprising a train controlling device located

in the trackway and including a winding, a relay located in the trackway, a path of low resistance for said winding including a contact on said relay, and means for at times supplying energy to said relay through said winding.

15. Railway traffic controlling apparatus comprising a section of railway track, a train controlling inductor located in the trackway and comprising a winding, a relay, a circuit for said relay controlled by traffic conditions in advance and including said winding, and means controlled by said relay for at times close circuiting said winding.

16. In combination, a section of railway track, a track relay for said section, a line relay associated with said track relay, a trackway train controlling device comprising a winding, a shunting circuit for said winding including a front contact on said line relay, and a circuit for said line relay controlled by said track relay and including substantially all of said shunting circuit except said contact.

17. Railway traffic controlling apparatus comprising a trackway device including a winding, a first circuit for at time close circuiting said winding, a second circuit including substantially all of said first circuit, and a trackway signal controlled by said second circuit.

18. In combination, a railway track, a track relay, a line relay, a trackway inductor including a winding, a circuit for said line relay including said winding and a contact on said track relay, a low resistance circuit for said winding including a contact controlled by said line relay, and a trackway signal controlled by said line relay.

19. In combination, a section of railway track, a signal associated with the section, a line relay controlled in accordance with traffic conditions, an isolated inductor circuit controlled by the line relay and including a checking relay for controlling the signal.

20. In combination, a section of railway track, a signal associated with the section, a line relay controlled by traffic conditions in advance, a trackway inductor having a circuit controlled by the line relay, and a checking relay in series with the inductor circuit for controlling the signal.

21. In combination, a section of railway track, a trackway inductor for said section, a signal associated with said section and having a proceed and a caution circuit, a winding on the inductor, a circuit for said inductor winding controlled by traffic conditions in advance and including a relay in series with the winding, and means for closing the proceed circuit for said signal when and only when said relay is energized.

22. In a railway traffic controlling apparatus, the combination with a section of track and a trackway signal, of a track relay con-

nected to the section, a line relay having a plurality of front contacts and controlled jointly by the track relay of the adjacent section and the section next in advance, a track-
5 way inductor, a winding on the inductor, a circuit for said inductor winding including a checking relay and a front contact of said line relay, said checking relay having a front contact, and a proceed circuit for the signal including a front contact of the checking re-
10 lay and a front contact of the line relay.

23. In combination, a section of railway track, a train controlling inductor located in the trackway and provided with a winding, an isolated circuit for said inductor winding controlled by traffic conditions in advance, a signal associated with said track section, and means for causing said signal to indicate "proceed" when and only when said isolated
15 circuit is closed.

24. In combination, a railway track, a track relay, a line relay, a trackway inductor including a winding, a circuit for said line relay including said winding and controlled by said track relay, a low resistance circuit for said winding including a contact on said line relay, and a trackway signal controlled by said line relay.

In testimony whereof I affix my signature.

30 FRANK L. DODGSON.
